UNITED STATES PATENT OFFICE.

FRED L. HANSEN, OF PLAINFIELD, ILLINOIS.

CYLINDER ROTARY BROOM FOR TRAFFIC-LINE-LAYING APPARATUS.

Application filed March 29, 1924. Serial No. 702,925.

To all whom it may concern:

Be it known that I, FRED L. HANSEN, a citizen of the United States, residing at Plainfield, in the county of Will and State 5 of Illinois, have invented certain new and useful Improvements in Cylinder Rotary Brooms for Traffic-Line-Laying Apparatus, of which the following is a specification.

My invention relates to apparatus for laying a traffic line upon streets or roadways such as are usually utilized for marking 10 streets or roadways to guide traffic.

In my application for Letters Patent filed January 15, 1924, Serial No. 686,353, I have 15 disclosed such a machine which, in a general way, comprises a supporting frame, means whereby the frame may be drawn along a roadway, means for steering the movement of the frame, means for guiding the steering 20 action, a kettle carried by the frame for containing the substance of which the line is to be laid, a nozzle for laying the line, a pipe line through which the substance is supplied from the kettle to the nozzle, road 25 cleaning devices carried in advance of the nozzle, a bin carried by the frame and adapted to carry a supply of sand and having a discharge throatway, a distributor chute in communication with the discharge throatway and having its distributing end adjacent 30 the roadway in alignment with the nozzle, distributing pins in said chute for distributing the sand over the line being laid, an agitator device cooperative with the discharge throatway to cause the sand to flow freely therethrough, and means to drive said agitator.

The present invention has for its particular object to provide a modified construction 40 of the road cleaning device which forms a part of the subject matter of my prior application.

In its generic nature the present invention provides a rotary brush of the cylinder of 45 barrel type mounted to turn on a horizontal axis with associated means whereby the brush may be angularly adjusted to different positions in a horizontal plane, as well as raised up out of contact with the road when 50 in use.

More specifically the invention comprises those novel details of construction, combination and arrangement of parts, all of which will be first fully described, then be specifically pointed out in the appended claim,

reference being had to the accompanying drawing, in which:

Figure 1 is a plan view of a portion of a traffic line laying apparatus embodying my invention, such apparatus being, in large 60 measure, illustrated diagrammatically.

Figure 2 is a side elevation of the structure shown in Figure 1.

Figure 3 is an elevation-section view looking in the direction of the arrow in Figure 1. 65

Figure 4 is a detail elevation of one of the adjusting supports for the brush.

Figure 5 is a cross section on line 5—5 thereof.

Figure 6 is a detail vertical section of a 70 modification of the main support for the brush.

Figure 7 is a cross section on the line 7—7 of Figure 6.

Figure 8 is an enlarged detail view of one 75 of the adjusting supports, parts being in section.

In the drawing, 1 represents the chassis frame of the road vehicle on which the tank 23 that contains the marking fluid is located 80 and on which the marking nozzle 24 and its associated parts are carried.

Secured to the chassis frame and to the 85 tank is a brush supporting frame consisting of a horizontal lateral support 78, a bracket 80 with a brace 81 and a longitudinal support 79, together with a slotted arc plate 82 as clearly indicated in the drawing.

Journalled in suitably located fixed bearings 62 and 63 beneath the bar 79 is a line 90 shaft 61 driven, in any suitable way, as by a sprocket 83 and chain 60, forming a suitable rotating part 85 of the vehicle, a take-up roller 84 being provided for the usual purpose.

77 designates a support which is fixed 95 to the brush sustaining frame and which has an angled extension 77^a, apertured to receive the bearing shank 69^a and the swivel arm 69, the latter having the bearing 69^b for the shaft 72^a of the brush 72. The swivel arm 69 has a bearing for the vertical shaft 67 which drives, through bevel gears 70 and 71, the brush.

The rear end of the brush shaft 72^a is 100 mounted in a slide 74 that is connected by bolt and slot connections 76 to a channelled support 75 in which the slide 74 is vertically adjustable. The shaft 67 is vertically slidably journaled in a bearing 66 that is car- 105 110

ried on the support 77 and is driven by bevel gears 64—65 from the line shaft 61.

The arc plate 82 is curved on a center which lies along the axis of the shaft 67.

5 The support 75 is adjustably secured to the slotted plate 82 by a suitable bolt, nut and washer 75^x, so that the axes of the brush may be positioned in the horizontal plane in various angles to the direction of the 10 travel.

If found desirable the support 77 may be made of two parts, 77^y and 77^z, adjustably connected by bolt and slot connections 77^x as indicated in Figures 6 and 7.

15 68 is a stop collar with a set screw located on the shaft 67. The shaft 67 has a suitable key slot 76^x and the bevel gear 65 has a suitable key 65^x to permit up and down movement of the shaft 67 as the brush is raised 20 or lowered out of or into operative position.

In Figures 6 and 7 I have shown a modified arrangement of the front support for the brush. The support is made in sections 77^y and 77^z, bolt and slot connected for vertical adjustment to cooperate with the similar structure of the rear support 74—75. By adjusting the parts 69 and 74 up or down 25 and tightening the connection 76, the position of the brush with respect to the 30 ground may be fixed and determined. By adjusting the position of the connection between the support 75 and the slotted arc plate 82 the angular position of the brush 35 may be adjusted with respect to the direction of travel.

By leaving the connection 76 (and the connection 77^x if the modification is used)

loose enough the brush can rise and fall to accommodate itself to road unevenness and the spring action of the vehicle.

40 Of course it is understood that when driving from place to place with the apparatus out of use for its intended purpose the brush 72 is raised up out of contact with the ground, after which the connection 76 45 may be tightened to hold the parts with the brush in the elevated position until its use is again desired.

From the foregoing description, taken in connection with the accompanying drawing, 50 it is thought the construction, operation and advantages of my invention will be apparent to those skilled in the art.

What I claim is:

An apparatus of the class described, a supporting structure including brush supports, 55 one of said brush supports comprising two slidably engaging vertically positioned elements, the lower one of which is provided with a brush shaft bearing, the other of said supports comprising two elements pivotally connected on a vertical axis, one of said elements having a brush shaft bearing, a brush having its shaft journalled in said 60 bearings, a countershaft lying with its axis coincident with the pivotal axis of said pivoted elements, gearing connecting said countershaft with the brush shaft and a driving shaft connected with said countershaft for turning the same, and means for 65 sustaining the first mentioned brush support for adjustment in an arc having as its 70 center the axis of said countershaft.

FRED L. HANSEN.
